ABSTRACT

A replaceable wear resistant liner for the wearing surface of an aluminum guide feed used on rock drills.

LINER FOR ALUMINUM DRILL GUIDE FEED

BACKGROUND OF THE INVENTION

The present invention relates to drill guides. More particular reference is made to an inexpensive, easily replaced liner for the guide feed of rock drills.

The use of aluminum shapes for drill guide feeds has been relatively common. However, the softness of aluminum results in wear which has required time consuming and costly replacements in the field. Also, the replacement operation usually requires the removal of the drill. The commercial alternative has been to use an all-steel drill guide feed which is heavy and cumbersome. This invention incorporates a liner in extruded aluminum drill guide feeds which will provide the following advantages:

1. Wear resistance and longer periods between shut downs.
2. A relatively simple and easy means of retaining and of replacing the worn element.
3. A means of attachment which is essentially self-retaining.
4. Availability and economy.

BRIEF DESCRIPTION OF THE DRAWING

FIG. 1 is an elevational view of a rock drill mounted on a drill feed guide.

FIG. 2 is an elevational, sectional view of an apparatus including a drill-mounting plate, a feed screw, a drill guide feed, a replaceable liner, and a means for retaining and releasing the liner.

DESCRIPTION OF THE INVENTION

Referring to the drawings wherein similar reference characters designate corresponding parts throughout the views, FIG. 1 shows the environment in which this invention operates, while FIG. 2 illustrates the apparatus comprising a liner 10 for an aluminum drill guide feed shell 12 which is loosely slideable in a groove 14 formed by the involuted portion 15 of the feed shell 12. A series of apertures 16 are drilled in the guide feed shell with a spacing of approximately, but not limited to, 15 inches. The apertures are located such that a recess 18 on a bolt 20 is flush with the bottom surface 22 of the groove 14. A washer 24 and a locking nut 26 retain the bolt 20.

To install the liner 10 in the drill guide feed shell 12 the bolts 20 are inserted into the aperture 16 with the recess 18 flush with the surface 22 of the groove. The liner is inserted 45 into the groove from either end. A washer 24 is installed with a locking nut 26 which is tightened until the shoulder 28 of the bolt 20 retains the back 30 of the liner against the back of the groove. Thus, as the drill mounting plate 32 is caused to traverse the guide 12 by the feed screw 34 it is supported on the steel liner 10. To replace the liner the nuts 26 are loosened, the worn liner is slipped out of the end of the guide

shell and inverted, or a new steel liner inserted into the guide, and the locking nuts retightened. Inversion can double the life of a liner, as the part is symmetrical, but the wear pattern generally is not. It is unnecessary to remove the drill to replace the liner. Further, if one or more of the locking nuts should vibrate loose, the recess of the bolt will restrain the bolt from interfering with the movement of the drill plate 32 and from working out of the aperture 16.

From the aforesaid, it may be seen that I have provided 10 new and improved means for accomplishing all of the objects and advantages of my invention. While this is the preferred embodiment of this invention, it can be readily seen that variations are possible, such as V-shaped liners, asymmetrical liners which lack the advantage of reversibility, the elimination of 15 the washer by providing the locking nut with a shoulder, or the use of internal threads at one end of the bolt.

I claim:

1. A guiding device for use with a rock drill comprising a drill guide feed shell of light metal composition having a rigid base section, two guide sections extending from the base defining therewith a recess for a rock drill feed screw, said guide sections comprising a body portion and an involuted portion which defines with the body portion a duct parallel to the longitudinal axis of the base, and ducts forming parallel guides for a drill mounting plate, and
25 a liner having two projections slidably inserted in each guide section duct to provide a channel for a drill mounting plate, and
the guide sections further having a plurality of spaced apertures aligned along the length of the section, wherein retaining members for each liner are positioned to secure the liner within the duct of the shell.
2. The guiding device of claim 1 wherein the feed shell is of aluminum composition, the base section is flat on one side, the 30 guide sections arcuately extend from the other side of the base having an inwardly involuted portion defining rectangular ducts, the apertures extend through the body portion of the guides parallel to the flat of the base section and contiguous with a duct wall, and
40 wherein the liner is of steel composition having a flat base with two symmetrical and parallel projections extending perpendicularly therefrom, and
wherein the retaining member is slidably positioned in the aligned apertures of the guide feed shell, further having a threaded portion, a restraining portion comprising a recess to slidably receive a liner projection, and a lip to abut with the end of the liner projection, and a positioning member with an enlarged shoulder threadedly mating with the retaining member whereby the retaining member may be axially positioned to secure the liner within the duct of the shell.
